UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

LIFTING AND RETAINING DEVICE FOR SLIDING WINDOWS.

Application filed April 14, 1922. Serial No. 552,549.

This invention relates to an improved lifting and retaining device for sliding windows and it has to do, more particularly, with a device for lifting sliding windows of the type generally used in automobile bodies and for retaining said windows in their closed position.

The principal object of my invention is to provide a simple and inexpensive device which may be readily attached to the window sash and by means of which the sash may be retained in its lifted or closed position and which also furnishes means for the attachment of a lifting strap to the window. 10 A further object of my invention is to provide means for fastening a lifting strap to a sliding window and means independent of the strap for retaining the window in lifted or closed position, so that the lifting strap is relieved of all strain when the window is closed. 15

Another object of my invention is to provide a member which is hinged to the window and to which a lifting strap may be connected, said member being provided with means adapted to be engaged by a stationary hook on the automobile body for retaining the window in closed position. 20

Further objects, and objects relating to details and economies of operation and construction, will definitely appear from the detailed description to follow. In one instance, I accomplish the objects of my invention by the devices and means described in the following specification. My invention is clearly defined and pointed out in the appended claims. A structure constituting a preferred embodiment of my invention is illustrated in the accompanying drawing, 30 forming a part of this specification, in which:

Fig. 1 is a fragmentary view in side elevation showing a portion of an automobile body and a window provided with my lifting and fastening device. 40

Fig. 2 is a sectional view, taken on the line 2-2 of Fig. 1; and

Fig. 3 is a view of my device in front elevation.

In the drawing, the same reference numerals refer to the same parts throughout the several views and the sectional view is taken looking in the direction of the arrows at the ends of the section line. 50

In general, my invention consists in providing a member which is movably secured to the window or to the window sash and which is adapted to engage over a stationary support therefor fixed on the automobile body, to retain the sliding window in its upper or closed position. This member is also connected to the lifting strap by means of which the window is raised from and lowered into the window well of the body. In order to permit this member to clear the hook in lowering the window into and raising it from the well, I find it desirable to hinge said member to the window or window sash. 60

Broadly speaking, and from the standpoint of the object attained, the retaining device comprises a metallic fastening member carried by the window, a co-acting metallic fastening member carried by the window ledge, one at least of which members is relatively movable with respect to its support to engage and fasten upon the other, and means for raising and lowering the window which bring the fastening members within operative range of each other. This latter means is the flexible lifting strap. 70

In the accompanying drawing, I have shown a device embodying my invention employed for lifting and for retaining in raised position a sliding or drop window of the type commonly used in a closed automobile body. Referring to the numbered parts of these drawings, the automobile body, 10, has a window opening formed therein in any usual or desired manner, as, for example, by inturned flanges to which the finishing strip, 11, is secured. If desired, the strip, 11, may carry a weather strip, 12, at the lower edge of the window opening, which is adapted to engage the window. In the construction of the body, a window well, 13', is provided, into which the window may be dropped. 80

when it is desired to leave the window opening open. My invention is not concerned with the details of structure of the window or the window opening, but has to do, more particularly, with a device for lifting the window from this window well and for retaining it in its upper position. The window, 13, slides from its upper position to its lower position in the window well and, as usual, the lower edge of the window is positioned in the metal channel, 14, with felt or similar packing, 15, interposed between the glass and the metal of the channel. The lifting and retaining device is preferably secured to this channel member. In the particular arrangement shown as an illustrative embodiment of my invention, I have provided a plate, 21, which is secured to the base of the channel, 14, by welding or in any other suitable manner. Spaced hinge knuckles, 22, are formed at one edge of this plate. A plate, 23, is provided with hinge knuckles, 24, at its lower edge, adapted to be brought into alinement with the knuckles, 22, the two parts being hinged together by the pintle, 25, passed through the alined knuckles. This plate, 23, is provided with an opening, 26, to receive a retaining device, 18, carried by the body, to support the window in its upper position. The upper edge portion of the plate, 23, engages around the lower reach, 28, of a loop, as indicated at 27. A lifting strap, 31, is looped around the upper reach, 29, of said loop, as indicated at 30. The inner sides of the window opening may be finished in any desired manner, as, for example, by the strips or moldings, 17 and 19. The retaining device consists of a stamping, 16, secured to the body and provided with an upturned finger, 18, which extends towards the window and into position to be received through the opening, 26, in the plate, 23, when the window is raised into its upper or closed position. The upturned finger, 18, is accommodated in a space, 20, formed by off-setting the finishing strips or moldings, 17, 19.

In practice, the operation of this device is very simple. In Fig. 2, the parts are shown in position for retaining the window in its upper or closed position. To lower the window the operator lifts on the lifting strap, 31, and raises the plate, 23, from engagement with the support, 18, swinging it, as he does so, toward the window about the hinge pintle, 25. This permits the plate, 23, to clear the support, 18, and the window may then be lowered completely into the well, or it may be retained in any intermediate position by fastening devices engaging the lifting strap, 31, in accordance with present practice. To raise the window to the closed position, the operator lifts on the lifting strap, 31, thus moving the window upwardly, in the ways provided there-

for. When its upper position is reached he swings the lifting strap, 31, and the hinged plate, 23, away from the window and lowers the window slightly so that the support, 18, passes through the opening, 26, in the plate, 23, to retain the window in the upper position. It is to be noted that, when the window is supported in its closed position, the lifting strap is relieved of all strain. In fact the body of the strap is entirely free of the retaining means when the window is fastened in raised position. The fastening members on the other hand being carried directly from the window and the window ledge are free of the body of the strap. A far more positive, much stronger and more flexible device results. Furthermore, the structure for retaining the window in its upper position is more or less flexible in nature, thereby permitting a yielding and sidewise movement of the window, due to flexing or vibration of the body as it is driven.

The construction illustrated in the accompanying drawing and described in this specification may be altered considerably, without departing from the spirit of my invention, and, therefore, I desire to claim my invention broadly, as indicated by the appended claims.

Having thus described my invention, what I claim as new and useful and desire to secure by Letters Patent is:

1. A device of the class described comprising the combination with a sliding window and a stationary fastening member positioned adjacent said window, of a plate secured to the lower edge of the window sash, a member hinged to said plate and provided with an opening in its upper portion, and a member secured to the upper end of said plate and bridging the upper end of said opening, said fastening member being adapted to extend through said opening and engage said bridging member.

2. A device of the class described comprising the combination with a sliding window and a stationary fastening hook positioned adjacent said window, of a plate hinged to the lower part of the window sash and having an opening in its upper portion, a cross member secured to the upper end of said plate, and a lifting strap secured to said cross member, said hook being adapted to extend through said opening and engage said cross member.

3. A device of the class described comprising the combination with a sliding window and a stationary fastening hook positioned adjacent said window, of a plate hinged to the lower edge of the window sash and having an opening in its upper portion, a loop secured to the upper part of said plate, and a lifting strap attached to said loop, said plate being adapted to be

swung on its hinge to cause said fastening hook to pass into said opening.

4. In a window lifting and retaining device a stationary retaining support in combination with a loop member, a plate movably connected at one edge to the window and at the other edge to one reach of the

loop member, said plate arranged to engage said support to retain the window in its raised position, and a lifting strap connected ¹⁰ to the other reach of said loop member.

In testimony whereof, I affix my signature.

JOSEPH LEDWINKA.
